UNITED STATES PATENT OFFICE

HARRY E. NELSON, DECEASED, LATE OF NEWTON, IOWA, BY FRANK E. HILL, ADMINISTRATOR, OF NEWTON, IOWA.

DESIGN FOR A WASHING MACHINE CASING

Application filed August 9, 1929. Serial No. 32,347. Term of patent 7 years.

To all whom it may concern:

Be it known that HARRY E. NELSON, deceased, late a citizen of the United States, and resident of Newton, Jasper County, Iowa, was the inventor of a new, original, and ornamental Design for Washing Machine Casing, of which the following is a specification, reference being had to the accompanying drawings, forming part thereof.

Fig. 1 is a side perspective view of a washing machine casing showing the new design, which would present substantially the same

appearance when viewed from the other three sides;

Fig. 2 is a top plan view of the same.

What is claimed is:

The ornamental design for a washing machine casing as shown and described.

In witness whereof, I have hereunto affixed my signature as administrator of the estate of the said HARRY E. NELSON, deceased.

FRANK E. HILL,
Administrator of the Estate of Harry E.
Nelson, Deceased.
